CLAIM

We claim the ornamental design for a flashlight, as shown and described.

DESCRIPTION

FIG. 1 is a perspective view of a flashlight, showing our new design;
FIG. 2 is a left side view thereof;
FIG. 3 is a top view thereof;
FIG. 4 is a right side view thereof;
FIG. 5 is a bottom view thereof;
FIG. 6 is a rear end view thereof; and,
FIG. 7 is a front end view thereof.

(Continued)

The broken lines are included for the purpose of illustrating portions of the flashlight that form no part of the claim.
